HARRY SANFORD GARDINER, OF AMSTERDAM, NEW YORK.

GAGE.

BEST AVAILABLE COPY

SPECIFICATION forming part of Letters Patent No. 765,471, dated July 19, 1904.

Application filed March 15, 1904. Serial No. 198,218. (No model.)

To all whom it may concern:

Be it known that I, HARRY SANFORD GARDINER, a citizen of the United States, and a resident of Amsterdam, in the county of Montgomery and State of New York, have invented a new and Improved Gage, of which the following is a full, clear, and exact description.

The invention relates to measuring instruments, and its object is to provide a new and improved gage, more especially designed for conveniently and quickly determining the sizes of twist-drills and other objects and to gage wires and the like.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a perspective view of the improvement as applied for gaging a wire. Fig. 2 is a rear face view of the improvement arranged for measuring a rectangular bar both in width and thickness. Fig. 3 is a longitudinal sectional elevation of the improvement on the line 3 3 of Fig. 2, and Fig. 4 is a transverse section of the same on the line 4 4 of Fig. 3.

The improved gage is provided with a frame or body A, having at one side a longitudinal extension-arm A', terminating at its outer end in a transverse gage-arm A², having its inner edge at right angles to the extension-arm A'. On one face of the frame A is formed a longitudinal guideway A³, in which is mounted to move longitudinally a slide B, adapted to be fastened in any desired position on the frame A by a suitable clamping-screw C, which when unscrewed also serves to move the slide B longitudinally into the desired place. The slide B is provided with an integral head B', having its outer edge parallel and adjacent to the inner edge of the gage-arm A², and on one face of the said slide B is arranged a longitudinal graduation D, indicating linear measurement, preferably in

thirty-seconds to three-quarters of an inch, as plainly illustrated in Fig. 2. On the head B' and on the same face of the slide B having the graduation D is arranged a second graduation E, also indicating linear measurement, arranged, however, transversely, starting from the inner end of the head adjacent to the arm A'. For measuring the size of a twist-drill, for instance, it is only necessary to pass the twist-drill between the arm A² and the head B' of the slide and then read off the size of the twist-drill on the graduation D along the bevel edge A⁴ on the inner end of the frame A. When it is desired to measure the width and thickness of a bar, as indicated in Fig. 2, then the bar is placed between the arm A² and the head B', abutting against the inner edge of the extension-arm A'. By reference to Fig. 2 it will be seen that the thickness of this bar can be read on the graduation D, and the width of the bar on the graduation E. On the other face of the slide B is arranged a graduation F, (see Fig. 1,) representing the size of wires and the like, the graduation consisting of transverse lines arranged in three adjacent longitudinal columns, and the lines are numbered according to wire-gage numbers and read off along the beveled edge of a cross-bar A⁵, forming part of the frame A and secured to the sides thereof opposite the beveled edge A⁴. These columns are preferably three in number, and the central column is provided with close graduations, while the graduations of the columns at the sides thereof are spaced twice as far apart and alternate with each other in extending from the middle of the spaces between the graduations of the central column.

In gaging a wire the latter is placed between the gage-arm A² and the head B', as plainly shown in Fig. 1, and then the size of the wire is read off on the graduation F—that is, on the line coinciding with the beveled edge of the cross-bar A⁵.

The instrument is very simple and durable in construction and can be cheaply manufactured and readily manipulated to obtain the desired size of twist-drills and the like or the gages of wires and similar round objects.

Having thus described my invention, I claim as new and desire to secure by Letters Patent—

1. A gage, comprising a flat frame having a guideway on one side, an extension-arm extending forwardly from the end of the gage, and terminating in a transverse gage-arm extending inwardly from the end of said extension at right angles thereto, the inner edge of said gage-arm being parallel with the forward end of the frame, a slide received into said guideway, and movable on the frame toward and from said gage-arm, an integral head on said slide projecting laterally from the side edges thereof to form a stop for the slide when moved rearwardly, a cross-bar on the upper face of the frame extending across the guideway at the forward end thereof, the front edge of said cross-bar and the corresponding front edge of the frame being beveled, the slide having on its front side a longitudinal graduation reading forwardly toward the head of the slide and terminating at said head, and a transverse graduation on the head reading outwardly from the rear side of the slide to the front side thereof, wire-gage graduations on the opposite side of the slide comprising transverse lines in separate columns, one of said columns having comparatively close graduations and the columns at the side thereof having graduations spaced twice as far

apart and alternating with each other in extending from the middle of the spaces between said close graduations, and a clamping-screw carried on said slide and adapted to engage the frame to lock the slide in any desired position thereon. 35

2. A gage comprising a frame having a guideway, an extension-arm extending forwardly from the end of the gage, and an integral inwardly-extending transverse gage-arm at the forward end of said extension-arm, said gage-arm being disposed at a right angle to said extension-arm and parallel with the forward end of the frame, a slide fitting in said guideway and movable toward and from said gage-arm, and an integral head on said slide to form a stop therefor, said slide being provided on one face with wire-gage graduations comprising transverse lines in columns, and on the other face with longitudinal and transverse graduations located respectively at the front side and forward end of said slide. 45 50

In testimony whereof I have signed my name to this specification in the presence of two subscribing witnesses.

HARRY SANFORD GARDINER.
